LOCKING POST CONSTRUCTION

James C. Dawson, Jr., Kirkwood, Mo.

Application August 3, 1942, Serial No. 453,314

4 Claims. (Cl. 129—13)

The present invention relates generally to loose-leaf binder constructions, and more particularly appertains to a locking post construction for maintaining separable binder elements in operative relation and for releasing the same.

An object of the present invention is to provide a novel compact post locking mechanism for loose-leaf binders.

Another object is to provide a novel self-locking post construction for loose-leaf binders of the ring-release type, which positively maintains the removable cover in operative relationship with the base, yet which readily releases to permit the removable cover to be displaced.

Another object is to provide a novel locking post construction for loose-leaf binders of positive operation of an over-all size to receive one of the perforations of sheets adapted to be contained by the binder.

Another object is to provide a novel post locking mechanism for loose-leaf binders of the dog type in which the biting characteristic of former constructions is eliminated.

Other objects are to provide a novel post binder locking mechanism for loose-leaf binders which is simple in construction, which in all-over diameter is small enough to receive a punched hole of sheets adapted to be contained by the binder in a preferred embodiment, and which is adapted to fulfill all of the objects and advantages sought.

Other objects and advantages will be apparent from the following description taken in conjunction with the accompanying drawing in which:

Fig. 1 is a plan view of a loose-leaf binder incorporating the present invention;

Fig. 2 is a bottom edge view of the binder shown in Fig. 1;

Fig. 3 is an enlarged section on the line 3—3 of Fig. 1;

Fig. 4 is a section on the line 4—4 of Fig. 3;

Fig. 5 is a plan view of the locking dog; and

Fig. 6 is an edge view of the said locking dog.

Referring more particularly to the drawing, 10 indicates generally a loose-leaf binder which includes an upper cover construction 11, a base construction 12, outer binder posts 13, and a central locking post construction generally designated 14 incorporating the concepts of the present invention.

The cover construction 11 includes a board member 16 covered with suitable outer flexible material 17, that extends over the back plate 18, forming a first hinge at 19. There is also an inner flexible cover 20, extending around the

inside of the plate 18, thence around the flange thereof, and upon the inner side of the board 16, forming a second hinge portion 21. This cover material may be in one piece if desired. A notch 22 is cut into the board 16 from the back edge thereof. It is surmounted by a plate 23, of metal or the like, beneath the cover 17; and the cover 20 is forced into the notch to line the same.

The base construction 12 includes a board member 25 covered by suitable material 26. A lower angle member 27 is covered by the material 26 in a manner to form the hinge 28. The relationship of the lower angle member 27 and the upper angle member 22, when in operative relation, is as shown in Fig. 3.

The locking post 14 is preferably the centrally disposed sheet receiving post of the binder 10. An outer cylindrical or tubular member 31 is secured at its lower end by a crimping process in an aperture 32 in the lower angle member 27. An inner cylindrical or tubular member 33, somewhat smaller than the outer one, is secured in the same manner at its upper end to the upper angle member 18 and is telescopically received by the cylindrical member 31. A shoulder member 35 is secured in and to the cylindrical member 33 near the upper end and receives, through a small aperture 36, a cotter pin 37 having an eye 38 to which is connected a split ring 39.

A dog 41 (Figs. 3, 5, 6) of a configuration to include a rearwardly extending tongue 42, and a scalloped front portion 43 having a rounded upper edge, is mounted in the cylindrical member 33 near the lower end thereof with the tongue 42 disposed in a slot 46 in the cylindrical member 33. The scalloped portion 43 is received in an enlarged cut-away portion 47 of the cylindrical member 33. The dog 41 preferably is bevelled at 49 along the rear edge of the tongue 42, and along portions of the perimeter around from the tongue 42. It is undercut along the scalloped front portion 43. The dog 41 receives the lower end of the cotter pin 37 through an aperture 50 and abuts against a collar 51 disposed about the lower end of the cotter pin 37, the collar 51 being maintained in position by a spread extreme end 52 of the cotter pin 37. A compression spring 54 is disposed about the cotter pin 37 and has the upper end abutting the shoulder member 35 and the lower end abutting the dog 41. The aperture 50 is toward the right in Fig. 3, so that the collar 51 may engage the inner surface of the cylinder 33, thereby preventing the tongue 42 from slipping out of its slot 46. The dog 41 is

restricted in its upward movement to an extent to prevent withdrawal of the tongue 42. The dog may be inserted through the notch 47, and thereafter the pin 37 and the collar 51 engaged thereon.

When the binder 10 is in closed position, the ring 39 is enclosed within the recess 22 so that a substantially smooth upper cover is presented as is apparent from Figs. 1 and 3.

Operation

After the hinge portion of the cover construction 11 is raised from the position shown in Fig. 2, the split ring 39 may be grasped to release the lock post construction 14. In Fig. 3, the dog 41 is in locking engagement with the outer cylindrical member 31, the edge of the tongue 42 and the scalloped front 43 being forced into engagement therewith through the action of the spring 54. This spring forces the tongue 42 down against the bottom of the slot 46, and then urges the dog toward a horizontal position in which the scalloped portion 43 and the tongue 42 engage with the inner walls of the cylinder 31. A fortuitous opening force tending to part the two cylinders 31 and 33, results in the inner cylinder's forcing the tongue 42 upwardly; but this merely causes the front edge of the dog to bind more tightly with the outer cylinder. Hence no appreciable separating movement can occur, as the binding is already initiated by the spring. If the tongue 42 be made slightly deeper than the distance from the inner to outer walls of the cylinder, an additional binding may occur between the tongue and the cylinder 31.

To release the lock post mechanism 14, the split ring 39 is drawn upwardly against the action of the spring 54. Since the collar 51 is contiguous to the lower surface of the dog 41, upward movement of the cotter pin 37 effects a pivotal action of the dog 41 about the engagement of the tongue 42 and the edge of the slot 46, to release the scalloped front 43 of the dog 41 from engagement with the interior surface of the outer cylindrical member 31. The release of the dog 41 may be effected without undue effort inasmuch as the scalloped front 43 is rounded at its upper edge which is the line of engagement. No biting into the interior of the outer cylindrical member 31 occurs due to said rounded upper edge. The cover construction 11 may be readily removed as soon as the foregoing action has been accomplished.

The ring 39 may be released immediately after the upper cover construction 11 has been separated from the base construction 12, and it is unnecessary to draw the cotter pin 37 upwardly again until another releasing action is required since the inner cylindrical member 33 may be telescopically reengaged with the outer cylindrical member 31 readily, for the angular disposition of the dog 41 permits free downward sliding movement.

It is apparent from the foregoing, that the post locking construction 14 is positive in its action, yet no biting of the dog 41 results, and, further, that the simplicity thereof permits use in a lock post construction of the standard post size, such as $\frac{3}{8}$ " or $\frac{5}{16}$ ", as well as larger sizes.

Not only does this construction involve a minimum of parts for the locking mechanism, but the parts are of small size, and the construction enables a reduction in size of the rear parts of the binders. The only extension necessary, back

of the posts, is an amount sufficient to receive the edge of the sheets.

It is manifest that there has been achieved a locking post construction which fulfills all of the objects and advantages sought therefor.

It is to be understood that the foregoing description and the accompanying drawing are given by way of illustration and example and not for purposes of limitation, the invention being limited

10 only by the claims which follow.

What is claimed is:

1. In a device of the kind described, a stationary tubular member, a movable tubular member telescopically engaging said first member, a locking member mounted in said second tubular member and engaging said first tubular member, when said tubular members are telescopically engaged to restrict telescopic movement in one direction, said locking member including a tongue 20 extending through said second tubular member and engaging said first tubular member and a scalloped portion in opposed relation to said tongue extending through said second tubular member and engaging said first member along 25 the scallops, said scalloped portion including a rounded upper edge forming the engaging line, said locking member being disposed at an angle to the axis of said tubular members, a shoulder member secured to and in said second tubular 30 member adjacent the upper end thereof, an elongated member extending through an aperture in said shoulder member and through an aperture in said locking member, said elongated member including an eye preventing passage of said 35 elongated member downwardly through said shoulder member, a ring secured to said eye, a collar secured to said elongated member adjacent to and abutting the underside of said locking member, a spring disposed about said elongated member having one end abutting the underside of said shoulder member and the other end abutting the upper side of said locking member, whereby movement of said elongated member upwardly releases said locking member from 40 engagement with said first tubular member to permit the aforesaid restricted telescopic movement.

2. In a mechanism of the kind described, a first tubular member, a second tubular member adapted to be telescoped into the first, a notch in the inner member having an upper edge extending a substantial angular distance around the member, an opening in the inner member opposite the notch, a dog having a first projection engaging in the opening and forming, with the opening, a pivot for the dog, the dog having an opposite portion in the notch, said dog being of a size to extend through the notch from the pivot a greater distance than that from the pivot to the inner wall of the outer member, whereby said opposite portion of the dog may pivot away from the open end of the outer member into engagement with said inner wall, said opposite portion having an angular dimension to engage the said inner wall for a substantial angular distance to avoid marring of said inner wall, releasing means extending through the inner member and engageable with the dog to draw the same about its pivot toward the open end of the outer member to remove its projecting portion from engagement with the inner wall of the outer member, and means resiliently urging the dog into said engagement in opposition to the releasing means.

3. In a mechanism of the kind described, a first tubular member, a second tubular member adapted to be telescoped into the first, a notch in the inner member having an upper edge extending a substantial angular distance around the member, an opening in the inner member opposite the notch, a dog having a first projection engaging in the opening and forming, with the opening, a pivot for the dog, said notch having an angular extent to permit insertion of the dog therethrough into the inner member, the dog having an opposite portion in the notch, said dog being of a size to extend through the notch from the pivot a greater distance than that from the pivot to the inner wall of the outer member, whereby said opposite portion of the dog may pivot away from the open end of the outer member into engagement with said inner wall, said opposite portion having an angular dimension to engage the said inner wall for a substantial angular distance to avoid marring of said inner wall, releasing means extending through the inner member and engageable with the dog to draw the same about its pivot toward the open end of the outer member to remove its projecting portion from engagement with the inner wall of the outer member, said releasing means having an element engageable with the inner wall of the inner member opposite the pivot, to prevent withdrawal of the dog from the notch, 30

and means resiliently urging the dog into said engagement in opposition to the releasing means.

4. In a mechanism of the kind described, a first tubular member, a second tubular member adapted to be telescoped into the first, a notch in the inner member having an upper edge extending a substantial angular distance around the member, a dog, said dog having a portion in said notch, interengaging means between said inner member and said dog opposite said notch, whereby said dog may pivot with reference to said inner member, said dog being of a size to extend through the notch from the pivot a greater distance than that from the pivot to the inner wall of the outer member, whereby said portion of the dog may pivot away from the open end of the outer member into engagement with said inner wall, said portion having an angular dimension to engage the said inner wall for a substantial angular distance to avoid marring of said inner wall, releasing means extending through the inner member and engageable with the dog to draw the same about its pivot toward the open end of the outer member to remove its projecting portion from engagement with the inner wall of the outer member, and means resiliently urging the dog into said engagement in opposition to the releasing means.
